(57) CLAIM

The ornamental design for a table, as shown and described.

DESCRIPTION

FIG. 1 is a front perspective view of the table of the present invention;

FIG. 2 is a top plan view thereof;

FIG. 3 is a bottom plan view thereof;

FIG. 4 is a front view thereof, the rear view being a mirror image thereof; and,

FIG. 5 is a left-side view thereof; the right side view being a mirror image thereof.

The broken lines depict portions of the table that form no part of the claimed design.

1 Claim, 5 Drawing Sheets
